UNITED STATES PATENT OFFICE

HARRY GORDON, OF BROOKLYN, NEW YORK

DESIGN FOR A SCARF

Application filed January 30, 1930. Serial No. 34,340. Term of patent 3½ years.

To all whom it may concern:

Be it known that I, HARRY GORDON, a citizen of the United States, and residing at #1788 St. Johns Pl., Brooklyn, N. Y., county of Kings, city and State of New York, have invented a new, original, and ornamental Design for a Scarf, of which the following is a specification, reference being had to the accompanying drawing, forming part thereof.

The drawing is a plan view of approximately one half of the scarf showing my new design, the opposite half being a repetition thereof in reverse position continued from the top of the drawing.

I claim:

The ornamental design for a scarf as shown and described.

HARRY GORDON.
